1888.

UNITED STATES PATENT OFFICE.

JOHN HAYS HAMMOND, JR., OF GLOUCESTER, MASSACHUSETTS.

BALANCED MODULATING REFLECTORS.

Application filed December 24, 1925. Serial No. 77,518.

This invention relates to musical instruments of the percussive type and more especially to pianofortes.

Broadly stated it is the principal object of the present invention to provide improved means for controlling damped musical sounds.

According to one feature of the invention a plurality of groups of modulating reflectors are provided and the reflectors of each group are balanced with respect to each other so as to be operated with very slight exertion on the part of the operator.

Other objects will appear from the following description taken in connection with the accompanying drawings in which

Figure 1 is a front elevation partly in section of a grand piano having features of the invention; and

Figure 2 is a bottom plan view of the piano of Figure 1.

Like reference characters refer to like parts in the several figures of the drawings.

In the following description and claims, parts will be identified by specific names for convenience of expression but they are intended to be as generic in their application to similar parts or the equivalent construction as the art will permit.

Referring to the drawings, there is shown so much of a grand piano 10 as is necessary to an understanding of the present invention and having applied thereto the features hereinbefore mentioned. In the embodiment illustrated the piano 10 includes a plurality of tuned strings such as 11 mounted in a frame 12. For vibrating the strings of each of the notes of the musical scale by percussion there is provided a suitable hammer action such as 13 operatively connected to each one of the keys 14 of the manual of the piano.

The strings are positioned within a casing 15 divided into two interior resonating chambers by means of a sounding board 16. A plurality of pedals such as 17, 18, 19 is mounted in a pedal block 20 below the casing 15. The pedals are operatively connected with rods 21, 22, 23 respectively. The two right hand rods 22, 23 are connected to the usual sustaino and loud pedal action of the piano which being well known in the art need not be more fully described.

The upper end of the left hand rod 21 engages one arm of a bell crank lever 26 which

is pivoted as at 27 and is maintained in the position illustrated in Figure 1 by means of a spring such as a leaf spring 28. The other end of the bell crank lever 26 is pivotally connected to one end of a link 30, the other end of which is connected to an arm 31, secured to a vertical shaft 32. The shaft 32 is mounted in bearings 33, 34 and is provided with a collar 35 to maintain the shaft in fixed longitudinal position with respect to its bearings. An arm 36 is affixed to the shaft below the lower wall of the casing 15 and is pivotally connected at its outer end to a link 37 extending to a reciprocating connecting rod 38. Similarly there is secured to the shaft 32 near the upper wall of the casing 15 an arm 39, the outer end of which is pivotally connected by means of a connecting link 40 to an upper reciprocating rod 41.

The casing 15 is provided with oppositely disposed controllable apertures as at 50, 51 (see Fig. 1). There is mounted in the upper aperture 50, a series of reflectors as at 53, serving to control the emission of sound. Each reflector 53 is preferably in the form of an elongated flat member having bevelled lateral edges and pivoted at one of its edges. Each reflector is provided on its inner surface with a layer 54 of sound reflecting material which may be of sheet metal having a smooth surface such as sheet aluminum, and is provided on its outer face with an arm 55. The outer ends of the arms 55 of the upper series of reflectors are pivotally connected to the upper connecting rod 41.

In the lower aperture 51 of the casing there is mounted a second series of reflectors to control the emission of sound. The construction of the lower group is similar to that of the upper group and includes for each reflector a sound reflecting layer on the inner face which in this case is the upper face. The outer ends of the arms 55 of the reflectors of the lower group are pivotally connected to the lower connecting rod 38. The reflectors of the lower group are pivotally mounted on one edge, and in the embodiment illustrated the two series of reflectors are so arranged as to reflect the sound towards the strings tuned to the treble notes of the scale, and so that as the force of gravity is exerted upon the reflectors of one of the groups to open them, for example, it also acts on those of the other group to tend to close them. The reflectors of the two groups

being similar in number and in construction, their weights are thus substantially balanced.

Surrounding the apertures the casing includes an upper wall 56 and a lower wall 57 skirting the respective apertures and having edges bevelled to conform to the edges of the contiguous reflector 53. The walls 56, 57 and the intermediate boundary walls of the casing 15 are provided on the interior with a layer of sound reflecting material which may be of sheet metal having a smooth surface such as sheet aluminum or the like. There are thus formed two resonating chambers, one designated by the reference character 60, extending between the upper series of reflectors and the sounding board 16 and the second resonating chamber designated 61 extending between the sounding board 16 and the lower group of reflectors.

It will be seen that the arrangement is such that the weight of the several reflectors of the lower group counterbalances the weight of the upper group of reflectors so that the reflectors can be moved easily.

In operation, the manual of the piano is employed by the musician in the usual way to cause vibration of the strings 11 in accordance with the music being played. In order to produce a desired effect let it be assumed that it is desired to sustain some of the notes of the music. Accordingly the pedal 17 is held down and thus the rod 21 is moved upwardly so as to rotate the bell crank lever 26 in a counter clockwise direction as seen in Figure 1. The connecting link 30 and the connecting rods 38 and 41 are moved to the right and thus the reflectors 53 of the upper group of reflectors are rotated in a clockwise direction and the reflectors of the lower group are rotated in a counter clockwise direction. Assuming that the pedal 17 has been fully depressed, the reflectors are thus adjusted into the fully closed position with the respective apertures closed. The reflecting surfaces 54 of the reflectors in combination with the reflecting surface of the fixed walls of the casing 15 serve to reflect the energy of the compressional waves produced by the strings back to the strings and sounding board to cause a reflex or regenerating action. The vibration of the strings and sounding board is thus effectively sustained for a considerable period.

When it is desired to emit at least a portion of the sound produced within the resonating chambers within the casing 15 the pedal 17 is raised somewhat and this motion is communicated to the reflectors 53 causing them to be partially opened. By raising the pedal to a desired degree any desired volume of sound up to the maximum may be obtained.

The invention upon which this application

is based is broader than the specific embodiment shown and described for the purpose of illustrating at least one of the ways in which it may be employed. The scope of the invention is therefore to be understood as not being limited by the present specific description. I intend no limitations other than those imposed by the claims.

What is claimed is:

1. A modulating system for a pianoforte, comprising a tone modulating pedal, a plurality of modulating reflectors each pivotally mounted on its lateral edge for variably controlling the volume of sound emitted from the instrument, said reflectors being arranged in two groups, and means operatively interconnecting said pedal and said groups of reflectors so that the weight of the reflectors counterbalance each other by groups, for operating the reflectors.

2. A modulating system for a pianoforte comprising a plurality of modulating reflectors arranged in groups, the reflectors of certain of said groups being pivotally mounted on their lateral edges respectively to reflect sound in a predetermined direction, the reflectors of others of said groups being mounted on their lateral edges respectively to counterbalance the weight of the reflectors of the first named group, and a single control device for operating all of said reflectors.

3. A modulating system for a pianoforte, comprising a pair of resonating chambers, each having a controllable aperture, a tone modulating pedal, a plurality of modulating reflectors for each of said apertures, each of the reflectors being pivotally mounted on its lateral edge for variably controlling the volume of sound emitted from the respective resonating chamber, a shaft operatively interconnecting the reflectors of one of said chambers with the reflectors of the other chamber so that the weight of the reflectors counterbalance each other, and means operatively interconnecting said pedal and said shaft for operating the reflectors.

4. A modulating system for pianofortes, comprising a casing, means within the casing for producing damped compressional waves, said casing having oppositely disposed controllable apertures for the emission of sound, a plurality of modulating reflectors for one of the apertures and pivotally mounted on their lateral edges respectively to rotate in one direction of rotation to open the respective aperture, a second plurality of modulating reflectors for the other aperture and pivotally mounted on their lateral edges respectively to rotate in the opposite direction of rotation to open the respective aperture, and means for actuating all of said reflectors.

5. In a sound producing instrument, a casing having openings, a source of sound within said casing, a plurality of separate clo-

sure devices for said openings, means for supporting said devices so that the weight of some balances the others, and means for operating said devices.

- 5 6. In a sound producing instrument, a casing having openings, a source of damped vibrations within said casing, a plurality of separate closure devices for said openings, means for supporting said devices so 10 that the weight of some balances the others, and means for operating said devices, said devices operating to reflect the sound.

7. In a sound producing instrument, a casing having a sounding board dividing 15 said casing into two chambers, each chamber having an opening, a source of sound within said casing, a closure device for each of said openings, means for supporting said devices so that the weight of one balances the 20 other, and means for operating said devices.

8. In a sound producing instrument, a casing having a sounding board dividing said casing into two chambers, each chamber having an opening, a source of damped 25 vibrations within said casing, a closure device for each of said openings, means for supporting said devices so that the weight of one balances the other, and means for operating said devices.

9. In a pianoforte, a casing having oppositely disposed openings, a source of damped vibrations within said casing, a plurality of modulating reflectors for said openings each pivoted at one edge, and means for mounting said reflectors so that those 35 for one of said openings balances the others, and means for opening and closing said reflectors simultaneously.

10. In a sound producing instrument, a casing having openings, a source of sound within said casing, closure devices for said openings, means for supporting said devices so that the weights thereof balance each other, and means for operating said devices.

11. In a sound producing instrument, a casing having openings, a source of sound within said casing, a plurality of separate closure devices of ponderable mass for said openings, means for supporting said devices 50 so that some of the weight thereof balances the remainder, and means for adjusting said devices to control the means of opening.

Signed at Gloucester, in the county of Essex and State of Massachusetts, this 55 twenty-second day of December, A. D. 1925.

JOHN HAYS HAMMOND, JR.
